REFRIGERATOR CABINET

Mortimer Frankel, Indianapolis, Ind., assignor to
 Fairbanks, Morse & Co., Chicago, Ill., a corpora-
 tion of Illinois

Application November 18, 1936, Serial No. 111,432

1 Claim. (Cl. 312—173)

This invention relates to improvements in refrigerators cabinets and the primary object of the invention is to provide a refrigerator having an auxiliary food compartment or chamber formed between a pair of doors, one of which constitutes the principal closure for the cabinet. With the described construction the inner door provides a closure for the inner, or main food chamber and serves to check the entrance of heat into the main chamber when the outer door is opened. The more frequently used articles may be stored in the auxiliary compartment on trays or racks mounted on the front face of the inner door which is adapted to be swung open to give access to the main chamber.

Another object of the invention is to provide an improved operating and latching arrangement for the plural door structure above mentioned, whereby both doors may be opened concurrently to render the inner chamber accessible, by a simple, single hand unlatching operation, and whereby an equally simple manipulation of the latch enables the outer door to be opened without disturbing the inner door.

A further advantage of the improved door operating and latching arrangement is attained in the facile manner in which the inner door may be opened after the user has opened the outer door, as for example, where it is desired to remove articles from the forward auxiliary compartment and transfer the same to the main chamber.

Other objects and advantages will appear from the following description which refers to a presently preferred embodiment of the invention illustrated by the accompanying drawings.

Fig. 1 of the drawings is a perspective view of a refrigerator with both doors shown in open position;

Fig. 2 is an enlarged sectional plan view of the front portion of the refrigerator, with the doors disposed in closed position, and showing the latch device for the inner door;

Fig. 3 is an enlarged, fragmentary sectional elevation of a portion of the refrigerator, showing means of a preferred type for automatically opening the inner door, the view being taken along line 3—3 in Fig. 2;

Fig. 4 is a detail view in plan of preferred enlarged sectional latch construction for the inner door;

Fig. 5 is a sectional elevation of the inner door latch mechanism as taken along line 5—5 in Fig. 4, and

Fig. 6 is a side elevation of the latch mechanism

as viewed in the direction of the arrow appearing in Fig. 4.

Referring to the drawings by characters of reference, the refrigerator cabinet, designated generally 10, has an upper space for food storage and a lower space occupied by a mechanical cooling unit (not shown). An outer door 11 and an inner door 12 are hinged supported from the jamb 13 and adapted to be latched in their respective closed positions by latching mechanisms, that mechanism for the inner door being mounted on the jamb 14. The outer door 11 may comprise, in accordance with conventional refrigerator door construction, an insulating panel 15 adapted to fit within the door opening and a face plate 16 adapted to lap the margins of the door opening. A sealing strip 17 of suitable material skirts the inner peripheral edge of the face plate. The outer door is supported on hinges indicated at 18 and may be secured in closed position by a suitable latch mechanism actuatable by handle 19 carried by the door.

Describing now the construction and arrangement of the inner door 12, such door preferably comprises a sheet metal panel having forwardly projecting marginal flanges in the manner of a shallow rectangular pan. Food shelves 20 are suitably mounted on the front face of the door, as best appears in Fig. 2. When both doors are disposed in closed position (Fig. 2) inner door 12 lies wholly within the refrigerator cabinet and the forward extremities thereof are spaced a short distance from the inner face of door 13. The inner door is dimensioned smaller than the cabinet opening to provide a marginal space between the same and the inner wall faces of the cabinet. Accordingly, cold air may circulate freely between the main and auxiliary compartments, through the space surrounding the inner door. Certain of the shelves 20 are provided at their forward edges 21 with rubber buffers for silent, shock-absorbing engagement with the outer door.

The inner door is carried by a pair of hinges 22, and one or both of which hinges include means, to be hereinafter described, for causing the door 12 to be moved automatically into open position when its latch is released and the outer door is open. Each hinge includes relatively long and short arms 23 and 24, respectively, pivotally interconnected in the conventional manner by a hinge pin 25. The jamb 13 at the hinged side of the outer door is suitably recessed to accommodate hinges 22, the pivotal axes of which are located near the forward edge of said jamb. Hinge arm 24 is fastened by screws 26 to a plate 27 and such

plate is secured to the jamb within one of the recesses, aforesaid, by screws 27A. Screws 28 serve to secure the door 12 to the longer hinge arm 23.

5 The self-opening means for the inner door, heretofore referred to, may desirably include a spring 29 (Fig. 3), which acts upon a plunger 30. The spring and plunger are mounted in a tubular housing 31, the assembly occupying a bore or 10 pocket in the door jamb. The plunger 30 projects through registering openings in hinge arm 24 and plate 21 for bearing engagement with hinge arm 23. Suitable means are provided for limiting the extent of plunger movement outwardly 15 of the housing, as for example, the enlarged head 32 at the extremity of the reduced plunger neck portion 33, which head abuts the inner end of the tubular housing 31 when the desired extent of plunger travel, outwardly, is 20 reached. The manner in which the spring and plunger assembly functions to open the inner door when the latch is released, and the way in which the plunger is reset by the door when closed will be apparent from Figs. 2 and 3.

25 The latching mechanism for the inner door is mounted on jamb 14, the mechanism being actuatable to release the inner door by means of a plunger, or push rod 34, which projects through the front face of the jamb and is located in 30 proximity to the outer door handle 19 when that door is closed. The door jamb 14 is provided with a recess 35 extending inwardly from the side face thereof, which recess is occupied by the latch mechanism, and a recess or opening 36 for push 35 rod 34 extending from recess 35 to the front face of the jamb. Mounted within a suitable case, designated 37, in the jamb recess 35, is a compound lever system comprising a so-called primary lever 38, and a secondary or latch lever made 40 up of two members 39 and 40 which are mounted for rocking movement on a common, vertical pivot pin 41. The substantially straight primary lever 38, mounted on a vertical pivot pin 42, is provided with bearing plates 43 and 44 at its opposite ends. 45 Bearing plate 43 engages the inner end of push rod 34, and bearing plate 44 operatively engages the shorter arm of secondary lever member 39. A torsion spring 45 carried by pivot pin 42 has a yieldable finger 46 which presses against bearing 50 plate 43 to maintain the same in operating contact with, and providing a spring return for the push rod. Suitable means are provided for limiting the extent of push-rod travel outwardly of the jamb, in the present example, such means including a plate 47 having an end slot 48 which accommodates a reduced portion of the push rod, the inner head end 49 of the push rod abutting the margins of the plate slot when the desired outward extent of push rod travel has been 55 reached.

60 The secondary lever member 39 is of the bell-crank variety, having a short arm 50 which, as has been stated, is operatively engaged by primary lever 38, and a long arm 51 disposed substantially at a right angle to arm 50. Lever member 39 is fulcrumed on pivot pin 41 by means of spaced lugs 52 located at the angulate bend of the lever. A torsion spring 69 disposed on the pivot pin has a yieldable finger 53 which presses 65 against the short lever arm, constraining the lever toward door latching position and holding the same in operating engagement with the primary lever, as best appears in Fig. 4. The longer lever arm 39 emerges from the jamb recess 35 toward 70 the rear of the cabinet and swings toward and

75 from the side wall of the cabinet for latching and unlatching engagement with the inner door. Arm 51 terminates in a U-band 54 which normally is disposed in the path of a flange 55, formed on the inner door, serving to limit the extent of inward door movement relative to the cabinet. The door flange 55 is desirably provided with a suitable rubber strike pad 56 which is held to the flange by the angulate end portion 57 of a striker plate 58, extending across the end face of the door. Lever arm 51 may strike the side wall of the cabinet when retracted to release the door and for purposes of cushioning the impact a rubber pad 59 is provided on the lever arm.

80 Associated with lever arm 51 is the catch member 40 which is pivotally mounted on pin 41 for independent movement relative to the associated lever arm. Catch member 40 is provided with an angulate nose portion 60 which projects through a slotted opening 61 in lever arm 51 for engagement with a forward corner 62 of strike 58. Movement of the catch member outwardly with respect to the lever arm is limited by the engagement of an end projection 63 on the catch member with the back side of the lever arm. The nose portion 85 of the catch member is normally held in projecting position relative to the lever arm by means of a torsion spring 64, one end 65 of which is suitably anchored to the short arm 50 of lever 39, and the other end 66 of which spring bears 90 upon the side of the catch member. Spring 64, by preference, is weaker than spring 69 which serves yieldingly to position the secondary lever assembly.

95 The members 39 and 40, comprising the secondary lever assembly, extend through an opening in a finishing or closure plate 67 fastened to door jamb 14 by screws 68 which also serve to secure the entire latching assembly to the cabinet.

Describing now the operation of the inner door 100 latch mechanism, assume that the outer door is in open position and it is desired to open the inner door. Push rod 34 is pressed inwardly to cause primary lever 38 to rock clockwise (Fig. 4) against the action of spring 45 and move the 105 secondary lever assembly in a counterclockwise direction against the action of spring 69. The nose 60 of the catch member is thus retracted to free the inner door flange 55, allowing the door, motivated by spring 29 (Fig. 3) to swing open. 110 When the plunger rod 34 is released, the described latch mechanism is restored by the springs to its normal condition which is shown by Fig. 4.

115 When the inner door is closed, the catch member and lever arm are sequentially cammed inwardly by the striker plate, inward movement of the door being ultimately checked by the bent end portion of the lever arm. The catch member springs back into latching engagement with the door flange and holds the door closed against the 120 opening force produced by spring 29.

125 In accordance with the specified objects of the invention it will appear that both doors may be opened concurrently and with but little manipulative effort by the simple operation of pressing the push rod 34 with the thumb of the same hand that is used to grasp handle 19 to open the outer door. The operating spring associated with the inner door causes the same to swing open smoothly and quietly, and without unduly disturbing articles carried thereby. The desirability of providing self-opening means for the inner door, and avoiding the use of means operatively connecting the inner and outer doors for their joint 130

opening by a pull or jerk on the outer door handle will be readily understood.

I claim:

In combination with a refrigerator cabinet having a forward opening and a food chamber accessible therethrough, an outer door hinged on the cabinet and providing a closure for said opening, an inner door hinged on the cabinet, adapted to divide the food chamber into forward and rear compartments, a cooling unit located in the rear compartment, shelves on said inner door for supporting food in the forward compartment, a latch element mounted on the cabinet

and cooperating with said inner door, a plunger for actuating said latch projecting from a forward wall of the cabinet adjacent the door opening, spring means operable to move the inner door outwardly of the cabinet when said latch is released, a latch for the outer door, a handle mounted on the outer door, operatively connected to the outer door latch for releasing the same, said handle and plunger being arranged for concurrent, single-hand manipulation when the outer door is closed.

MORTIMER FRANKEL.
